UNITED STATES PATENT OFFICE.

MAHLON E. LAYNE, OF MEMPHIS, TENNESSEE.

METHOD OF COLLECTING AND PUMPING WATER.

1,286,666.

Specification of Letters Patent. Patented Dec. 3, 1918.

Application filed April 3, 1917. Serial No. 159,390.

To all whom it may concern:

Be it known that I, MAHLON E. LAYNE, a citizen of the United States, residing at Memphis, in the county of Shelby and State of Tennessee, have invented certain new and useful Improvements in Methods of Collecting and Pumping Water, of which the following is a specification.

This invention relates to a method of collecting and pumping water from shallow water bearing formations and has for its principal object the increasing of the flow of water which can be obtained.

Heretofore, where the water bearing formation is more or less shallow and has salt water bearing strata immediately below, it has been found difficult if not impossible to operate the pump at its maximum capacity, for by so doing the supply of fresh water immediately surrounding the pump was quickly exhausted, when if the operation were persisted in, salt water would gradually flow in from beneath and thereby render the supply objectionable for use. To overcome this difficulty it has been the custom in many localities to install a number of pumps, more or less closely adjacent to one another as the conditions required. By operating these pumps considerably below capacity, it has heretofore been possible to draw a supply of water in something like usable quantities, from such shallow water bearing formations as have been mentioned. It is one of the objects of this invention to reduce the number of pumps or to substitute for a number a single pump capable of supplying practically the same quantity of water which was supplied by the many.

Previously when single pumps have been used the water, as was said above, was rapidly exhausted from the formation immediately surrounding the pump, thus permitting the pressure of the atmosphere to work down into the ground thereby breaking the vacuum created by the suction of the pump. As a consequence, it not being possible for the fresh water to flow in rapidly enough from the sides, salt or otherwise objectionable water flows up from beneath and is pumped to the surface.

It is the specific object of my invention

to increase the area affected by the vacuum of the pump so that a greater volume of fresh water may be obtained from a single pump. In general the method by which I obtain this result consists in sealing a certain portion of the gathering area or collecting space immediately surrounding the pump against atmospheric pressure. This causes the effect of the vacuum of the pump to be felt in a much greater radius than before and consequently increases the area from which the pump draws, thereby giving a greater and more constant flow of water. This sealing of the collecting spaces against atmospheric pressure is accomplished by saturating with water a certain area of the formation surrounding the pump, and is more specifically described below.

I have illustrated my new method of collecting and pumping water in the accompanying drawings, wherein—

Figure 1 is a vertical section wherein the water bearing strata consists of sand immediately subjacent to a stratum of clay which is in turn immediately subjacent to the top soil; Fig. 2 is a plan view illustrating the manner in which the sealing water is distributed; Fig. 3 is a partial section illustrating a method of treating formations which do not contain clay; Fig. 4 is a section which illustrates the application of my invention to rock formations; and Fig. 5 is a plan view of the arrangement shown in Fig. 4 illustrating the method used for distributing the sealing water.

Referring to Fig. 1, the pump is indicated by the numeral 7 which in this case is of the rotary impeller type although other types may be used. The pump pit 8 extends down into the fresh water bearing sand 9 and terminates in the screen or strainer 10. The pump is operated by a belt from any suitable source of power by means of the pulley 11, the water discharging from the pipe 12 into the trough 13 from which it is distributed by the pipe 14. A portion of the water discharged is conducted by means of the pipe 15 to the circular distributing tile 16 located just below the top soil 17 and immediately above the clay formation

18. The circular tiling may be extended over any area desired as individual conditions seem to indicate. These sections of circular distributing tile 16 are connected and brought into communication with the source of supply by means of the main distributing tile 19 (see Fig. 2). By this means the clay above the water bearing sand 9 is kept constantly wet over an extended area 10 surrounding the pump, and forms an excellent seal against atmospheric pressure from above. It will thus be seen that the effect of the vacuum of the pump will now be felt not only in the immediate vicinity 15 of the pump, but also at the extremity of the extent of the wetted clay. Instead of drawing from an area of small diameter the supply will be drawn from an area of greatly increased diameter with a consequent 20 increase in the flow of water.

In some localities the water bearing sand may not be subjacent to clay, or other soil suitable for use in the manner described above as a seal against the pressure of the 25 atmosphere. In such instances I excavate the formation above the water bearing strata, substituting clay at the bottom of the excavation, (see Fig. 3). Broken rock or stone 19 is then filled in as an aid to the 30 distribution of the sealing water by means of the tile 16 which is placed immediately above the rock or stone. Some of the excavated matter is last thrown in and forms the surface or top soil. In the method just 35 described, it will be understood that it is not always necessary to have clay, other soils being satisfactory, but clay is preferable as it is usually easily available, at low cost and will not crack if the ground should settle, 40 thereby breaking the seal.

Figs. 4 and 5 illustrate my method as applied to rock formations, also shallow. From the pump as a center, crossed concrete troughs 20 are built out into the area which 45 is to be used to form the seal over the gathering or collecting space. These troughs are built to a depth about equal to that of the pump and have constructed immediately below them the culverts 21. The side walls 50 of these troughs do not extend quite to the surface of the ground. Somewhat more shallow troughs or ditches 22 are constructed as an aid to the distribution of the sealing water and extend between main 55 troughs. All of the troughs and ditches are filled with broken rock, cinders or stone 24, (shown in Fig. 4 but omitted in Fig. 5) as an aid to the distribution and to prevent their being filled with dirt or refuse. Part 60 of the water discharged from the pump is led by means of the pipe 23 into this system or network of troughs, which after being filled overflow and fill the interstices of the rock immediately surrounding the pump

which is generally very porous, especially 65 in coral formations such as exist for example in Key West, Florida. This of course, substantially seals a certain area against atmospheric pressure from directly above, and as in the case previously described, where clay was used to form the seal, the pump draws from the extended area surrounding this seal instead of from the small area immediately adjacent the pump pit. 70 75

It will be seen that my method is very simple, and that the efficiency of a single pump is greatly increased and the necessity of so great a number of pumps obviated. It will further be evident that the water 80 distributing means, as shown in Figs. 1, 2, and 3, being located underneath a covering layer of soil will provide an effective seal with a minimum requirement of water and such arrangement will also avoid rapid loss 85 of water by evaporation and thus further increase the area that may be sealed for a given pump.

I claim:

1. In a method of collecting liquid in 90 wells from which it is pumped, the step which consists in determining the extent of the effect of the pump vacuum by sealing an area surrounding the suction pipe of the pump against atmospheric pressure from 95 above.

2. In a method of collecting liquid in wells from which it is pumped, the step which consists in determining the extent of the effect of the pump vacuum by water 100 sealing a predetermined area of the collecting space against atmospheric pressure.

3. The herein described method of obtaining water from shallow formations which consists in water sealing a predetermined 105 area against atmospheric pressure from above and in drawing the water from beneath the protecting area.

4. The herein described method of obtaining fresh water from formations having salt 110 water bearing strata immediately below, which consists in water sealing a predetermined area against atmospheric pressure from above and in drawing the water from the protected area lying between the salt 115 water strata and the seal.

5. The method of obtaining water from shallow water bearing formations subjacent to soil other than clay which consists in removing the soil from an area, in applying 120 a layer of clay to the bottom of the excavation thus made, in covering the clay with broken rock or stones, in providing means to wet the clay, and in pumping the water from beneath the wetted clay. 125

6. In a method of pumping water, the step which consists in increasing the extent of the effect of the suction of a pump by

sealing with wet clay an area beneath the surface surrounding the pump against atmospheric pressure.

7. The method of obtaining water from shallow water bearing formations subjacent to soil other than clay which consists in removing the soil from an area, in applying

ing a layer of clay to the bottom of the excavation thus made, in providing means to wet the clay, and in pumping the water 10 from beneath the wetted clay.

In testimony whereof I have hereunto signed my name.

MAHLON E. LAYNE.
